SURGICAL OR MEDICAL VEIN DILATING DEVICE

Czeslaw Antoni Florian Uhma, Sydney, Nova Scotia, Canada, assignor to Surgic Company Limited, Sydney, Nova Scotia, Canada, a body corporate of Nova Scotia

Application February 27, 1957, Serial No. 642,815

13 Claims. (Cl. 128—345)

This invention is concerned with the provision of improved surgical or medical devices for intravenous use in blood transfusion operations or in the introduction into a vein of therapeutic or other liquids or substances or in the introduction of therapeutic or other liquids into other ducts or cavities of the body or withdrawal of inflammatory fluids from such ducts or cavities. The object of the present invention is primarily to provide an introducing device which will enable intravenous or intraduct or intracavity insertion of tubing of considerable diameter to be effected without adopting the usual method of "cutting-down" to the vein or incision to expose the ducts or cavities, and the consequent difficulties and delay entailed in exposing the vein, duct or cavity by incision and traumatising the anatomical structure. The device also has the advantage that the vein and its function are not permanently destroyed, which would otherwise occur by ligation of the vein during the "cutting-down" procedure.

The invention will be exemplified by reference to the accompanying explanatory drawings whereon:

Fig. 1 is a side view of the complete instrument (in inverted position).

Fig. 2 is a plan view of the instrument.

Fig. 3 is a plan view of the lower component and inserted needle.

Fig. 4 is an inverted plan view of the upper or removable component, and Fig. 5 is an end view thereof.

Fig. 6 is a sectional view on section line 6—6 of Fig. 3.

Fig. 7 is a perspective view illustrating a modified form of the instrument.

Fig. 8 is a side view and Fig. 9 is an end view taken on the section line 9—9 in Fig. 8.

Fig. 10 is a view similar to Fig. 8 showing the upper component raised about its hinge, and Fig. 11 is an end view on section line 11—11 in Fig. 10.

Fig. 12 is a side elevation of a dilating pin.

Referring firstly to Fig. 1, the instrument comprises a lower component A, an upper component B, and a surgical needle C. The component A is shown in plan in Fig. 3 and comprises an elongated trough-shaped member or gutter 14, preferably made of metal, to the outer end of which is secured a short hollow needle or tubular bush 15. The inner end of the gutter 14 merges into a tube or elongated bush 16 which is secured in a groove in a member 17 from which a handle 18 laterally extends.

The surgical needle C has a finger grip 19 secured thereto in order to enable the needle to be pushed through the aligned bushes 15 and 16 until the beveled end or point 20 of the needle C projects beyond the outer end of the gutter 14, as shown in Figs. 1, 2 and 3.

The instrument also comprises the upper detachable component B shown detached in Figs. 4 and 5 and which consists of an elongated trough-shaped member or gutter 21 of smaller width than the gutter 14. The gutter 21 may be beveled off at its outer end at 22 and is secured at its inner end to a plate 23 which has a lateral extension 24 forming a hand grip for the gutter 21. The gutter

2

21 may be made from a tube 25 split longitudinally at 26 and opened out to form a spatulate end 22. The plate 23 is adapted to be temporarily attached to the plate 17 by any suitable means, as by pins 27 on the plate 23 engaging holes 28 in the plate 17, so that the gutter 21 overlies the gutter 14 and extends up to the bush 15.

Alternatively, the plate 23 may be detachably engaged with the plate 17 by means of a tongue or tongues on one member slidably engaging in a groove or grooves in the other member.

The instrument may be used for introducing polyethylene or other tubing into a vein either by the use of the components A, B and C together, or by the use of components A and B, or by the use of the component A alone, in which latter case the short hollow needle 15, which is beveled at its end at 29 to a sharp point, serves for introducing the component A into a vein.

When a vein is of large diameter and the tubing to be introduced is small, the component A alone can be used, it being understood that the components A and B will be made in various sizes to suit different vein sizes. Having selected a component A of suitable size for the vein, the short needle 15, which forms the outer end of the gutter 14, is introduced into the vein and advanced until the widest part of the gutter 14 reaches the lumen of the vein. The previously applied tourniquet is then released and the polyethylene or other tubing of suitable diameter is introduced through the gutter 14 and hollow needle 15 into the vein.

Where the vein is not of sufficient size to permit of the adoption of the above-mentioned operation, the component A is used in combination with the surgical needle C as shown in Fig. 3, using a component A of suitable size. After venepuncture, the needle C is advanced along the vein lumen for a distance of say about one and a half inches, and the needle C is then held in position by pressing the hand grip 19 against the skin of the patient, the needle C being of sufficient flexibility for this to be accomplished. The component A is then pushed along the needle C and into the vein until the gutter 14 enters the vein lumen. As the short needle 15 and tube 16 of the component A slide along the needle C, the latter serves as a guide for the entry of the short needle 15 and gutter 14 into the vein. When the widest part of the gutter 14 has entered the vein lumen, the needle C is withdrawn and removed, leaving the gutter 14 in the vein, when the polyethylene or other tubing can be introduced into the vein through the gutter 14.

In cases where the vein is to small for either of the above methods to be adopted and it is thought that the component A may traumatize and cut the vein, the three components A, B and C are assembled together as in Figs. 1 and 2 and the complete instrument is employed as follows: After the needle C and gutters 14 and 21 have been inserted into the vein lumen, the component B and needle C are removed and the tubing is introduced as before through the gutter 14. Flow of blood through the needle C as it is being advanced, serves as an indication of the correct position of the needle in the vein.

To enable the component A to be manipulated by either hand during introduction into a vein, a handle such as 18 may extend laterally from each side of the member 17.

The modified construction illustrated in Figs. 7-11 embodies the same three components, A, B and C, but in this case the gutter 14 is secured to lugs 30, projecting from a lever or finger piece 31 and the gutter 21 is secured to a lever or finger piece 32 which has lugs 33 hinged to the lugs 30 by hinge pins 34. A spring 35 interposed between the finger pieces 31 and 32 normally urges the gutter 21 into contact with the gutter 14 as seen in Fig. 8,

and by pressing the finger pieces 31 and 32 together, the gutter 21 can be raised from the gutter 14 as shown in Fig. 10. The needle C passes along the bottom of the gutter 14 through a hole 36 in the finger piece 31. Holes 37 in the finger pieces 31 and 32 permit of the introduction of a pin 38 (Fig. 12), whereby the gutter 21 may be lifted from the gutter 14 to dilate the vein into which the instrument is introduced. In order to enable the component B to be removed from the instrument, the hinge pins 34 may be removable, or the components A and B may be detachably hinged together in any other convenient manner.

In some cases, the component B need not be removable, in which case the gutters 21 and 14 may be permanently hinged together and the ethylene or other tubing which is to be introduced into a vein may be introduced through the holes 37 into the gutter 14 after the needle C has been withdrawn.

I claim:

1. A dilating device for intravenous use for the purpose hereinbefore stated comprising an elongated trough-shaped member tapering towards one end thereof, a short hollow needle fixed to said tapered end for entry into a vein until the vein is dilated by said member, and a finger piece attached to the other end of said member for manipulating the device.

2. A device as specified in claim 1 including a hollow longer surgical needle slideable through said short needle and extending longitudinally through said trough-shaped member.

3. A dilating device for the purpose hereinbefore stated, comprising a hollow elongated component tapering towards one end and slit longitudinally into a plurality of sections capable of being dilated outwards at the convergent end of said component, and a short hollow needle fixed to the narrower end of one of said sections, said needle being parallel or nearly parallel to the longitudinal axis of said component.

4. A device according to claim 3 including lever means attached to the wider ends of said sections to enable the narrower ends of said sections to be moved apart.

5. A dilating device for intravenous use comprising a hollow elongated component tapering towards one end and slit longitudinally into a plurality of tapered trough-shaped sections connected together at their wider ends and capable of being spread apart at their convergent ends, a short hollow needle fixed to the narrower end of one of said sections, and a longer surgical needle slideable longitudinally through said component and through said short needle.

6. A dilating device for the purpose hereinbefore stated, comprising a substantially conical elongated component divided longitudinally into two substantially complementary sections, said sections being attached together at their wider ends by means permitting the narrower ends of said sections to move apart, and a short needle attached to the narrower end of one of said sections, said needle being parallel or nearly parallel to the longitudinal axis of said component.

7. A device as claimed in claim 6 including a longer hollow surgical needle extending longitudinally along the inside of that section to which said short needle is attached, said longer needle being slideably fitted through said shorter needle.

8. A dilating device for intravenous use for the purpose hereinbefore stated comprising a substantially conical elongated hollow component divided longitudinally

into two substantially complementary tapering trough-shaped sections, means detachably attaching said sections together at their wider ends, and a short hollow needle secured to the narrower end of one of said sections and located in or parallel to the longitudinal central axis of said component, said means permitting the longitudinal insertion between said sections and through said needle of a hollow surgical needle of greater length than said component.

9. A dilating device as specified in claim 8 wherein said means comprises a two-part hinge whereof the two parts are detachable from each other to enable the sections of said component to be removed, one from the other.

10. A dilating device as specified in claim 8 including a finger piece fixed to said surgical needle for facilitating insertion and withdrawal of said surgical needle through said component and short hollow needle.

11. A vein dilating device for the intravenous introduction of tubing into a vein, comprising an elongated trough-shaped member having a tapered end, a finger piece secured to the other end of said member, a short hollow needle secured to the tapered end of said member and located longitudinally with respect to said member, a tubular bush at the end of said member adjacent said finger piece, a longer surgical needle slideable through said bush and short needle for effecting vene-puncture and removable through said bush to permit introduction of said short needle and the tapered end of said member into the vein, and a finger piece secured to said surgical needle for manipulation thereof.

12. A device as specified in claim 11 including an elongated covering element for the trough of said trough-shaped member, said element tapering at its end adjacent said short needle, a finger piece secured to the other end 35 of said element adjacent the finger piece on said member, and means removably attaching said element to said member.

13. A vein dilating device for the intravenous introduction of tubing into a vein, comprising a complementary pair of trough-shaped members tapering towards one end to provide a hollow tapering cavity between them, hinge means hingedly connecting the wider ends of said members, spring means normally urging said members towards each other, a short hollow needle secured to the tapered end of one of said members and opening at one end into said cavity and having its other end pointed, a longer hollow surgical needle slideable through said hinge means and cavity and through said short hollow needle, and a finger piece secured to said surgical needle for manipulation thereof through and withdrawal from said cavity, said hinge means permitting said members to be moved apart against the action of said spring means and thus permit tubing to be passed through said cavity into a vein dilated by said members.
